CLAIM

We claim the ornamental design for a foam buffering pad, as shown and described.

DESCRIPTION

FIG. 1 is a top perspective view showing a side face contour and a back face of the foam buffering pad.

FIG. 2 is a bottom perspective view showing a front face contour of the foam buffering pad.

FIG. 3 is a top view showing the back face of the foam buffering pad.

FIG. 4 is a sectional view taken on line 4—4 showing a contour of the back face of the foam buffering pad. The oblique hatching lines in FIG. 4, and the section lines in FIG. 3 showing the perspective from which FIG. 4 is taken, are for illustrative purposes only and form no part of the claimed design.

FIG. 5 is a bottom view showing the front face of the foam buffering pad; and,

FIG. 6 is a side view showing a side face contour of the foam buffering pad. All other side face contours of the foam buffering pad are identical to FIG. 6.

The surface shading lines are for illustrative purposes only and form no part of the claimed design.
